UNITED STATES PATENT OFFICE.

WILLIAM B. POTTER, OF SCHENECTADY, NEW YORK, ASSIGNOR TO THE GENERAL ELECTRIC COMPANY, OF NEW YORK.

TROLLEY.

SPECIFICATION forming part of Letters Patent No. 651,055, dated June 5, 1900.

Application filed January 11, 1898. Serial No. 666,327. (No model.)

To all whom it may concern:

Be it known that I, WILLIAM B. POTTER, a citizen of the United States, residing at Schenectady, in the county of Schenectady, State of New York, have invented certain new and useful Improvements in Trolleys, (Case No. 630,) of which the following is a specification.

My present invention relates to trolleys for electric railways having overhead conductors. It is particularly adapted to constructions where it is difficult to make the trolley-alinement coincide with the direction of the track. It is also useful with a number of conductors, as on the metallic return or polyphase systems, where the ground forms no part of the circuit. To fulfil its purposes, I provide a head for the trolley which is rotatable and in the case of a multiplicity of conductors also has a lost-motion connection of some sort, such as a ball-and-socket joint with limited play, with the trolley-pole. By this means in a system having a number of conductors I provide for the automatic individual adjustment of the different trolley-wheels to their respective conductors, so that the liability to displacement of the trolley is greatly reduced. Between this rotatable head and the base of the trolley I provide a suitable gearing, such that, irrespective of the direction of track or position of the trolley-pole, the head will be maintained in alinement with the conductors. In one of the forms of the device I have a plate rotatable upon the trolley-base, having two positions in which it is held fast by a suitable detent or lock, so that the trolley may be reversed. Between this plate and the head wires or cords extend, so that the head and plate form a sort of parallel-motion device. In another form the trolley-head is geared to the plate, as above constructed, by a shaft passing through the pole, the shaft being connected to the plate by a similar parallel-motion device.

While the particular forms of the invention illustrated are believed to be well adapted to its exercise, they may be varied without departing from its principles.

I have illustrated the invention applied to a car in Figure 1, which is a perspective view of a polyphase-conductor system. Fig. 2 is a side elevation, partly in section; and Fig. 3,

a plan of the trolley device shown in Fig. 1. Figs. 4 and 5 are respectively a side elevation and plan of a modified form of trolley-head. Figs. 6 and 7 are respectively a side elevation and plan of the second form of the device named in the statement of invention.

In Fig. 1, A is the car, and B the trolley. The trolley-head is lettered C and is provided with wheels c^3 c^4 c^5 , which are upon the angles of an equilateral triangle. These wheels travel, respectively, upon the conductors 1 2 3, (the usual trolley-wires,) provided with strain-insulators 8 9 and suitable insulated trolley-ears 5 6 7. The span-wire 4 serves to sustain the construction.

The device will be better understood from Figs. 2 and 3, where it is shown on an enlarged scale. Referring first to the trolley-head, upon a shaft C^2 swivels a suitable frame carrying the wheels. Each of the wheels is insulated from the frame, and it is to be understood that the insulated conductors are carried down the trolley-pole in any convenient way, so as to make the connection with the motors ordinarily used. A cross-arm C' is also provided, and this arm is connected to the base by the wires c^1 c^2 , respectively, attached to its ends. A shield c^6 is arranged to prevent the trolley catching in the span-wire should it become disengaged from the conductors. The vertical pivot C^2 , around which the head plays, is mounted on a ball which fits in a socket, giving it a limited rocking movement, so that the three corners of the triangle may adjust themselves to the different positions of the trolley-wires. As is well known, it is practically impossible to string the three wires in parallelism at all points. A base-plate E is provided for attaching the trolley to the car. In this plate rotates the trolley-pole on a stud E'. The socket b' of the pole is of the usual form, but is provided with a lug b³, which registers with a notch in the plate E². In the notch one or the other of the tumblers e e' rests when the trolley is in either of its operative positions. The spring b² is of the ordinary form. When it is desired to reverse the trolley, the pole is depressed in the usual way. The lug b³ engages with the tumbler e' and forces it below the level of the plate E². The pole is then

swung around, the plate holding both of the tumblers down until the notch in it comes opposite the tumbler e , which then rises and stops the rotation, the plate being thus locked 5 while the trolley is in its operative positions. Upon the plate E^2 are lugs $e^2 e^3$, to which the wires $c' c^2$ are attached. The operation of the parts thus described is as follows: One of the tumblers $e' e'$ being in engagement with the 10 plate E^2 and that plate being fixed, therefore, relatively to the base, the lugs $e^2 e^3$ are also fixed, while the trolley-pole and base may rotate about the stud E' , carrying with it the trolley-head; but this, it will be observed, is 15 maintained by the wires $c' c^2$ parallel to the track, so that if the trolley-conductors be upon one side or the other of the center of the track but are still following substantially its alignment the trolley-head C will be maintaining good contact. This form of the invention is well adapted to those locations where the trolley-conductors are at the side of the track, so that the trolley-pole projects at an angle to the course of the car. 20

25 In Figs. 4 and 5 I show at D a different form of trolley-head. The wheels $c^3 c^4 c^5$ are carried upon springs $d' d^2 d^3$. In this case a fixed stud d acts as a vertical axis for the trolley-head, the ball-and-socket joint being 30 unnecessary, as the springs give the requisite flexibility for accommodating the wheels to different heights of wire.

In Figs. 6 and 7 in place of the long wires $c' c^2$, connecting the trolley-head C and the 35 base, I substitute beveled gears $F F'$, working by the shaft f , passing through the trolley-pole. The shaft has attached to the lower one of the gears a cross-arm f' , to which the wires $c' c^2$ are attached, the rest of the base 40 construction being the same as in Figs. 2 and 3. I show this feature of my invention applied to a single-trolley system; but it will be evident that it is also applicable to double or other multiple trolley systems. It will also 45 be evident that the improvements described above are not restricted to three-trolley systems.

Of course the usual motor-conductors and insulating arrangements are provided for the 50 trolley, as well as the ordinary trolley-cord. Particular illustration or description of these well-known adjuncts is unnecessary.

What I claim as new, and desire to secure by Letters Patent of the United States, is—

- 55 1. A trolley device having a pole, a relatively-movable head, and a fixed base, and connections between the base and head maintaining the head substantially parallel with a fixed plane.
- 60 2. A trolley device having a pole, a rotatable head, and a fixed base, with gearing between the base and head so that the head is maintained substantially parallel to a fixed plane in all positions of the trolley-pole.

3. A trolley device having a pole, a fixed 65 base, a rotatable head, and a number of trolley-wheels with gearing between the base and head, so that the head is maintained substantially parallel to the track in all position of the pole. 70

4. In a trolley, the combination of a pole, a rotatable head, a base, and gearing between the base and the head, the base having a rotatable part which is locked in one or the other of two positions when the pole is making contact with the conductors. 75

5. A trolley, comprising a number of trolley-wheels mounted upon a rotatable head, a trolley-pole, a fixed base for the trolley with respect to which the pole may rotate, and a 80 parallel-motion device connecting the trolley-head with the base.

6. A trolley for a railway system with several line conductors, having a pole, a rotatable trolley-head with a number of wheels 85 thereon, and a universal joint between the pole and the head, so that the different wheels may adjust themselves to their respective conductors.

7. A trolley for a railway system with three 90 line conductors, consisting of a pole, a head having three wheels at the angles of a triangle, a universal joint between the pole and the head, and a base to which the pole is swiveled. 95

8. A trolley comprising three contact devices adapted to engage separate trolley-wires, one of which devices is mounted out of alignment with the other two, and all of which are carried by a trolley-pole. 100

9. The combination of three line conductors and a contact device for each conductor, one of said contact devices being located out of alignment with the other two. 105

10. The combination of a trolley-pole, a trolley-head movably connected thereto, and three contact devices triangularly mounted on said head and adapted to engage separate trolley-wires. 110

11. The combination of a trolley-head with three triangularly-arranged contact devices carried thereby and adapted to simultaneously engage a plurality of trolley-wires, and means for insulating the contact devices from each other. 115

12. The combination of a trolley-pole, a head pivoted thereto and carrying a plurality of grooved contact devices, a plurality of line conductors, and a parallel-motion device for maintaining the grooves of the contact devices in line with the conductors in all the working positions of the trolley-pole. 120

In witness whereof I have hereunto set my hand this 10th day of January, 1898.

WILLIAM B. POTTER.
